Term of patent 7 years

(Cl. D48—4)

To all whom it may concern:

Be it known that we, Allen O. Boutelle and Robert C. Kuder, citizens of the United States, residing at Jefferson, Jefferson County, and State of Wisconsin, and Fort Atkinson, Jefferson County, and State of Wisconsin, respectively, have invented a new, original, and ornamental Design for a Tube Lamp Fixture, of which the following is a specification, reference being had to the accompanying drawing, forming part thereof.

Figure 1 is a view in perspective of a tube lamp fixture, showing my new design.

Figure 2 is a view in side elevation of the tube lamp shown in Figure 1.

Figure 3 is a view in front elevation of the tube lamp shown in Figure 1.

Figure 4 is an end elevation of a tube lamp shown in Figure 1.

Figure 5 is a detail view taken in cross section on the line 5—5 of Figure 2.

Figure 6 is a detail view in cross section taken on the line 6—6 of Figure 4. The back of the fixture is plain.

We claim:

The ornamental design for a tube lamp fixture, as shown and described.

ALLEN O. BOUTELLE.
 ROBERT C. KUDER.
